WATER COOLER

Christopher M. Cordley, Greenwich, Conn., assignor to Cordley & Hayes, New York, N. Y., a corporation of New York

Application June 7, 1935, Serial No. 25,370

5 Claims. (Cl. 62—141)

This invention relates to improved devices for cooling and dispensing liquids and more particularly to water coolers and dispensers.

In water coolers of the ordinary type employing ice as the cooling medium, water is usually placed in a chamber surrounded by such ice, or it may pass through such a chamber, being drawn out thereof as needed. The ice is usually cracked into relatively small pieces to obtain a maximum cooling effect. The purpose of breaking up the ice, however, is defeated to a large extent, if large voids or spaces are formed between the various pieces so that appreciable amounts of air are enclosed in the ice chamber. I have discovered that if the ice chamber walls are so constructed that they converge towards the bottom thereof, the ice settles down in the chamber as it melts, remaining compact throughout the period of its usefulness, and thus securing a more efficient cooling action. This action is greatly enhanced by providing a taper on both the inner and outer surfaces defining the ice compartment.

My improved cooler construction embodies several novel features and in general is so designed that the casing or cabinet may be made of sheet metal with a minimum of expense and the various parts may be assembled and formed into a unitary structure by welding such as by spot welding.

30. A further feature of my invention is a novel waste bucket construction and the manner in which a bucket may be removably supported by the cabinet, with a portion of said bucket projecting from said cabinet to serve as a convenient receptacle for water, cups, and other waste.

Other features and advantages of my improved construction will appear from the detailed description of one embodiment of the same, applied to the inverted bottle type of water cooler, which 40 will now be given in conjunction with the drawings, in which:

Figure 1 is a front view of an assembled water cooler.

Figure 2 is a horizontal section taken on line 45 2—2 of Figure 1.

Figure 3 is a vertical sectional view through substantially the center of the cooler shown in Figure 1, looking toward the left thereof.

Figure 4 is a horizontal sectional view on the line 4—4 of Figure 1, and

Figure 5 is a perspective view of a tray member adapted to be inserted in the waste bucket.

In the drawings, numeral 10 indicates a cooling and dispensing cabinet adapted to support an inverted bottle 11 in the top thereof. This cab-

inet is made up of sheet metal side pieces 12, a back section 13 and a front section 14. The back and side sections are perfectly plain, while the front section is cut out along the line 15, 16 and 17 and bent inwardly along the line 18 to form a support 19 for the waste bucket 20. This support may be braced in any desirable manner as by the angularly disposed strip 21 which may be welded to the support and the front panel or otherwise fixed in place. The side, back and front sections have inset vertical edge portions 22 so that angle pieces 23 may be fitted thereover and fixed in place, as by spot welding, to form a smooth continuous exterior. It will be understood that in applying paint or other coating to the cabinet the juncture between the edges of the angle members and the main portions of the panels may be practically concealed. Thus, the outside of the cabinet presents a pleasing appearance, and may be much more easily cleaned than cabinets of the prior art. The angle members 23 are longer than the side sections and extend down below the bottom edges of such sections to form supporting legs 24 for the cabinet, having turned under and rounded ends 25 forming feet 25. therefor.

A suitable distance below the top of the cabinet there is provided a partition 26, which may be bent at its edges 27 for welding to the side, back and front sections. A bucket shaped member 28 30. may be placed in the cabinet above this partition having a lip 29 resting on a depressed flange portion of a member 30 at the top of the cabinet. The member 30 is welded or otherwise secured to the four panels and closes the top of the cabinet 35. outside of the member 28. This bucket shaped member is illustrated as circular in cross section, although any desired cross-section may be employed, and it is provided with side walls sloping inwardly toward the bottom thereof which may 40 advantageously be corrugated to increase its strength. Loosely resting within said member is an earthenware jar 31 having walls diverging outwardly toward the bottom thereof and having a suitable rim 32 at its top enlarged and formed 45 to hold a gasket 33 of rubber, or other material, for supporting the inverted bottle 11. By sloping the walls of the members 28 and 31 in opposite directions at a small angle of, say, 5 to 10 degrees to the vertical, as shown, an ice compartment is formed that is much larger in cross sectional area at the top than at the bottom. This insures proper packing of the ice as it melts. The jar 31 may be of any suitable material which does not affect the taste of the liquid to be dis- 55

pensed, although I prefer to employ some form of earthenware for this purpose. Near the bottom of jar 31 there is an opening through which a tubular stem 34 of a suitable spigot 35 may be 5 passed. This stem 34 also passes through openings in the side walls of the member 28 and the front section 14 and may be held in place by suitable nuts 36 and 36', acting in conjunction with suitable shoulders 36'' on the stem along 10 with washers if desired. Such a type of spigot arrangement is conventional and any other suitable device may be used.

Another spigot or outlet 36a of known construction is employed which communicates with 15 the interior of the chamber formed by bucket shaped member 28 and jar 31, and may be used to draw off melted refrigerant from time to time. This outlet is preferably arranged so that it is directly over a portion of the waste receptacle 20.

20 Insulating material 37 such as ground cork or the like may be employed between the outermost walls and the walls of the bucket 28 to minimize the loss of heat and preserve the cooling action of the refrigerant. The jar 31 may simply rest on 25 the base of the receptacle 28, or it may be supported some distance thereabove. As illustrated, the spigot arrangement 34 serves to hold the jar 31 in place, centrally of the member 28. With 30 its relatively large base there is little or no danger of tipping over. A suitable cover member for the cabinet may be employed which is preferably made up in two sections 38 and 39. These cover sections have overhanging edges 38' and 39' extending down over the four walls of the cabinet 35 and semi-circular openings 40 to fit around the walls of jar 31. Suitable stop members 41 may be employed on the under side of these covers to prevent them from sliding outwardly away from the jar. The meeting edges of the cover members may also be provided with overlapping 40 or interlocking extensions to insure a good fit and maintain the sections in place. These cover members also aid in maintaining the jar 31 in its correct position when they are fitted in place.

45 Waste bucket 20 is inserted in the opening in the front section of the cabinet so that approximately half of said bucket remains projecting from said cabinet. The lip of the bucket inside the cabinet is held in place by an overhanging portion 42' of a spring clip 42. This spring clip 50 may be welded to the partition 26 at one end 43, while the other end 44 may be free to slide on said partition so that the spring as a whole may be pressed upwardly as the bucket is inserted and withdrawn. The forward face of the spring 55 clip is inclined to provide a camming action as the bucket is forced into place. A member such as shown in Figure 5 may be inserted in the bucket to act as a shelf therein and to largely 60 conceal any unsightly accumulation of waste water and other material. This shelf member 45 may be made of a single sheet of metal or other material, bent at right angles to form a semi-circular section 46 and a vertical rectangular section 47, the top of which is curled about pins or rods 48. An opening 49 may be provided 65 at a point directly below the outlet of the spigot 35 to take care of overflow water, and another opening 50 may be formed, as shown, to permit 70 paper cups and other material to be dropped into the waste bucket proper. The ends of rods 48 are adapted to rest on the upper edge of the bucket 20 along the same plane as the front section 14. The outer edge of the semi-circular portion, or shelf 46, may be supported by a

5 bracket 51 welded to the side of the waste bucket 20. Thus a handy waste receptacle is provided with a shelf for holding cups to be filled, and at the same time having an opening to receive waste cups and through which the level of the waste water can be noted.

While my invention has been particularly described with reference to the use of an inverted bottle for supplying water, it is apparent that water may be supplied to the jar 31 from any 10 other source or the jar may be replaced by a coil of pipe suitably connected between a source of supply and the spigot stem 34.

My improved cabinet and bucket can be manufactured very easily, and inexpensively, due to 15 its simplified construction, since all parts may be simply stamped out of sheet metal and assembled and united by spot welding or the like.

Other solid refrigerants than ice may be employed in this cabinet if desired. 20

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed. 25

What I claim is:

1. In a liquid dispensing device, a cabinet made 30 up of one piece front, back and side sections the edge portions of said sections being offset inwardly, and angled corner members overlying and uniting the offset portions of said sections to provide a smooth exterior for said cabinet, one 35 of said sections having an opening and a tongue extending from the lower edge of said opening into the interior of the cabinet to form a shelf for supporting a waste receptacle within said opening. 40

2. In combination with a liquid dispensing device comprising a cabinet, a wall of said cabinet having an opening therein formed by cutting out a portion of said wall, said portion being bent 45 inwardly to form a shelf at the base of said opening, a waste receptacle in said opening and partly resting on said shelf, and means in said cabinet to releasably hold said receptacle in place. 45

3. In combination with a liquid dispensing device comprising a cabinet, a wall of said cabinet having an opening formed therein and formed with supporting means at the base of said opening, a waste receptacle in said opening resting on 50 said supporting means, a portion of said waste receptacle projecting outside said cabinet, and a tray in said projecting portion of said receptacle, 55 said tray comprising a horizontal section and a vertical section, said vertical section being substantially in the same plane as the said wall of said cabinet, and means at the upper corners of said vertical section for supporting the tray on the rim of said receptacle. 60

4. In a liquid cooling and dispensing device, a cabinet made up of one piece front, back and 65 side sections the edges of said sections being offset inwardly, angled corner members overlying and uniting the offset portions of said sections to provide a smooth exterior for said cabinet, a chamber in the cabinet thus formed adapted to hold a sub-divided, solid refrigerant, and a compartment inside said chamber for holding the liquid to be cooled. 70

5. In combination with a liquid dispensing device comprising a cabinet, a wall of said cabinet 75

having an opening therein and a tongue integral with said wall and extending into the interior of the cabinet to form a shelf at the base of said opening, a waste receptacle in said opening resting on said shelf with its upper edge closely adjacent the top of said opening, a portion of said waste receptacle projecting outside said cabinet,

and a tray in said projecting portion of said receptacle, said tray comprising a horizontal section and a vertical section, means at the upper corners for supporting the tray on said upper edge of said receptacle with its vertical section lying substantially in said opening. 5
